UNITED STATES PATENT OFFICE.

ADDISON PEASE, OF MONTEVIDEO, ASSIGNOR OF ONE-HALF OF HIS
RIGHT TO SAMUEL BUNDOCK, OF ORTONVILLE, MINNESOTA.

MAGAZINE FIRE-ARM.

SPECIFICATION forming part of Letters Patent No. 228,778, dated June 15, 1880.

Application filed April 26, 1879.

To all whom it may concern:

Be it known that I, ADDISON PEASE, of Montevideo, in the county of Chippewa and State of Minnesota, have invented certain new and useful Improvements in Magazine Fire-Arms; and I do hereby declare that the following is a full, clear, and exact description of the invention, which will enable others skilled in the art to which it appertains to make and use the same, reference being had to the accompanying drawings, and to letters of reference marked thereon, which form a part of this specification.

In the drawings, Figure 1 is a side sectional view of the interior with the parts in the position assumed after firing. Fig. 2 is the same view, showing the position of parts after drawing the trigger T back, thus making the weapon to cock itself. Fig. 3 is a perspective view of the breech-piece H, showing especially the vertical dovetail grooves U U, that engage and hold the flanges of the cartridges. Fig. 4 is an end view of the barrel and magazine. Fig. 5 is a detail, explained farther on.

The whole operation of the fire-arm is described as follows: Everything is supposed to be in position, as shown in Fig. 1. The magazine M is fed with as many cartridges as it will hold, of course placing the percussion ends of said cartridges in first. Small springs s s s, riveted to the interior of the magazine, prevent the cartridges from sliding back, but, being flexible, do not prevent them from going toward the breech-piece H. A small cover, c, kept shut by a small spring at the hinge, protects the magazine from dampness or rain. Other springs, s' s' s'; similar to the springs s s, before spoken of, are attached to the sliding bar r, and the inward movement (or to the right on the drawings) of this bar r forces, by means of these springs s' s', the cartridges toward the breech-piece H, and on the return of this bar r (or to the left in the drawings) the flexibility of these springs s' s' s' allows said springs to bend as they go past the cartridges, while those springs that are attached to the magazine M hold the cartridges still, thus allowing the bar r, on its next inward movement, to shove the whole gang of cartridges along still farther. The manner of causing

this movement of the bar r will be described farther on.

The position in Fig. 1 presupposes the magazine full of cartridges, and also shows a cartridge, supposed to have just been discharged, 55 remaining in the breech end of the barrel B. The forefinger, after discharging the fire-arm, remains on the trigger T. Now boldly pull back the trigger T as far as it will go. The trigger T swings on its fulcrum o, and at first 60 is all that moves; but in a short time the shoulder x' on said trigger T bears against the under side of the little cube at the end of the arm W. This action results in drawing downward the end of the breech-piece H, holding the discharged cartridge. This downward movement goes on until the end of the bar B' passes below the shoulder m on the hammer C. Now, a continuance of the pulling on the trigger T causes two things: first, the upper surface of the breech-piece H to pass slightly downward and also toward the stock O; secondly, 70 the wheel Y, at the stock end of the breech-piece H, to slide back between the ways or guides z z. Next a shoulder, L, in Fig. 3, on 75 the back side of H, impinges against the friction-roller y, rigidly secured to the hammer C. This impact causes the hammer C to turn back on its fulcrum p until a ratchet-tooth locks it back by springing back of a similar tooth at 80 n under the arm W. The weapon is then cocked, and everything has assumed the position shown in Fig. 2.

Now, before we release the trigger T from the finger, we will remark two other things that 85 have meantime been done. The first is that there is a stout spring, g, rigidly fixed at one end to the stock, and at the end next to the breech-piece H bent at right angles, so as to enter the slot h in the breech-piece H; but the 90 backward movement of the trigger T causes this bent end of the spring g to pass beyond the end of the breech-piece H and to pass out of the slot h. The moment this occurs, there being no longer anything to hold the 95 bent end of g down, the said bent end flies violently upward to a position opposite the end of the slot k in the breech-piece H. Now, as the bent end of g is below the exploded cartridge, still held in the vertical 100

grooves U U at the end of the breech-piece H, this violent upward movement of the spring g forcibly ejects the exploded cartridge from the weapon, as shown at * in Fig. 2. The 5 other thing that has meanwhile been done during all this back action of the trigger T, &c., is this: The said trigger T has impinged against a small latch, D, attached to a thin flexible flat spring, x, set on edge vertically, 10 and attached to the bar r, before alluded to. It will then be seen that any backward movement of the trigger T causes a similar backward movement to the bar r, and must continue to do so as long as the trigger T bears 15 against the latch D. Now, there is also what is called a "feed-regulator," for a long or short cartridge. A pin, I, having the lower end thereof formed into a bent and flattened part, E, and by small stops underneath the weapon 20 rendered capable of a revolution about its axis of one hundred and eighty degrees, and held up by a flat spring, h', riveted to the lower of the guides or ways Z, is provided, and supposed to have its lower end, E, turned to the 25 left, as shown in Fig. 1. When in this position the trigger T presses against the latch D during all of the backward movement of the trigger T, and gives the movement to r for a long cartridge. Now turn E to the right one 30 hundred and eighty degrees. A flattening or dishing out of part of I presents I to the latch D in such a shape that the latch D is wedged away from the trigger T, the flexibility of the spring x permitting this. Of course, if T is 35 pulled back any more, such pulling is inoperative now upon the bar r, which has ceased to move the moment the latch D was crowded away from the trigger T, and thus a feed is gaged for a short cartridge. In short, as Fig. 40 5 shows it clearly, for a long cartridge D is wedged inside of the pin I, and T continues to bear against D; for a short cartridge D is wedged outside of the pin I, and T ceases to bear against D, but goes on past the same. 45 It is also to be here stated that there are two sets of each of the springs, s and s', respectively, and they are placed longitudinally apart (on the bar r, and on the inside of the magazine M, as shown in Figs. 1, 2, and 4) at the proper 50 distances to suit the respective lengths of a long or short cartridge. The backward movement of T, it is thus seen, has caused the exploded cartridge to be ejected. As the breech-piece H first begins to descend the lower ends of the vertical grooves U U in the breech-piece H slide over the percussion end of the next cartridge, lying ready at the breech end of the magazine M. The spring s' on the bar r nearest the breech end of the magazine M is so placed on the 55 bar r as to insure the cartridge being brought sufficiently near to the breech, and a toe on the end of the spring A keeps said cartridge from going too far, and makes sure of the percussion end of the same entering the grooves U U. The under side of the breech-piece H then presses down the spring A, so that its toe 60 lies below the cartridge. Then H, moving backward, allows A to snap up again to the position shown in Fig. 2, ready for next time. An inclined plane, K, lying under H, causes 70 H to rise, as it is pulled back, until H passes over the inclined plane K, when H drops, as a result of the continued backward movement of the trigger T. The inclined plane K still being beneath the cartridge, causes the same 75 to rise to the proper height in the grooves U U, and while H is descending a small bar, h', kept toward the left in the drawings, Figs. 1 and 2, by a spring, b, latches into H as h' goes past the end of the inclined plane K. Mean 80 time the cartridge has got above h', and when the breech-piece H returns, as just about to be described, h' springs to the left again and locks the cartridge up to the proper height in the grooves U U of the breech-piece H, to enter the 85 barrel B when it is time so to do. Now suddenly let go of the trigger T. Instantly the recoil of the spiral spring S (which has been compressed by pulling H back) sends H and T 90 violently forward to their first positions, as in Fig. 1, except that the hammer C stays locked back ready for the discharge of the next cartridge. The spring g enters the slot k, slides back, and drops into the slot h, the direction 95 of these slots h and k again springing g down ready for another operation. The fresh cartridge is landed into the position shown in Fig. 1. The bar r is also sent back for a new charge of cartridges, as in the return the trigger T constantly impinges against the end of the slot in r through which the trigger T passes. A spring, g, keeps the trigger constantly forward, and also insures a sufficient pressure of the same against the end of the slot in r, just spoken of. 105 The firing is then simply effected as follows: A slight pull on the trigger T raises the shoulder x' on the same against the block or cube on the end of the arm W. W is raised sufficiently (against the pressure of a small spring, w, 110 that holds the same down) to release the ratchet-tooth from the notch at n. A stout spring, t', then sends the hammer C violently forward. The shoulder m on the hammer C snaps hard against the hammer-bar B', which is laid in a 115 hole passing lengthwise through the breech-piece H. The other end of B' transmits this blow to the percussion end of the cartridge lying ready in the barrel B, and the firing is accomplished. The hammer-bar B' may lie so as 120 to adapt it for either a center or a rim fire cartridge, as may be desired in making the fire-arms. 125 It is furthermore here remarked that the upward tendency of the spring g crowds the breech-piece H constantly up to position, especially on the recoil of the spring S; but what is finally relied on for this purpose is the spring A, heretofore described, and which may readily be seen to accomplish the said office in Fig. 1. 130 There are also guides on the side of the weapon for the breech end of the breech-piece H, one

of which is shown at J in Fig. 2. A channel in the side of H (after H has descended low enough to admit of being drawn back) guides H by means of J, as does also the inclined plane K, and when H returns to the position shown in Fig. 1, and has sprung up to place on account of the upward spring of A, this projection or guide J acts (as also do the corners N N in Fig. 3) as a shoulder to present a firm resistance to the recoil from the discharge of the weapon.

The guard G of the trigger T has a flat piece, F, riveted as a hinge at F', and not in use in Fig. 1. It is shown dotted in Fig. 2 as revolved on its hinge F' one hundred and eighty degrees, and locking the trigger T back against the recoil of the spiral spring S. This is convenient for cleaning, &c., of the breech-piece H.

Having thus described the working of my invention, I desire to claim and secure by Letters Patent as follows:

1. In a magazine fire-arm, the combination of the trigger T, the holding-down spring q, the arm W, the spring w, the spring t', the hammer C, the breech-piece H, the hammer-bar B', and the spring a, whereby the weapon is fired, all substantially as described.

2. In a magazine fire-arm, the combination of the trigger T, the latch D, the spring x, the bar r, having its springs s' s', and the pin I, having its spring k', substantially as and for the purposes described.

3. In a magazine fire-arm, the combination of the trigger T, the breech-piece H, the friction-roller Y, working between the ways Z Z, the spring S, and the spring g, working in the slots h and k of the aforesaid breech-piece H, whereby the cartridge is ejected after firing, all substantially as described.

4. In a magazine fire-arm, the combination of the trigger T, the breech-piece H, having the slots or grooves U U to engage a cartridge, the latch-bar h', the spring b, the inclined plane K, the spring A, the friction-roller Y, working between the ways Z Z, and the spring S, whereby cartridges are drawn from the magazine M and placed in position for firing, all substantially as described.

In testimony that I claim the foregoing as my own I affix my signature in presence of two witnesses.

ADDISON PEASE.
